Primary Examiner — Sheryl Lane*Assistant Examiner* — Calvin E Vansant(74) *Attorney, Agent, or Firm* — Berg Hill Greenleaf Ruscitti, LLP(57) **CLAIM**

The ornamental design for a multi-functional LED headlamp, as shown and described.

DESCRIPTION

FIG. 1 is a perspective view of the multi-functional LED headlamp showing our new design;

FIG. 2 is a front elevation view thereof;

FIG. 3 is a rear elevation view thereof;

FIG. 4 is a left side elevation view thereof;

FIG. 5 is a right side elevation view thereof

FIG. 6 is a top plan view thereof; and,

FIG. 7 is a bottom plan view thereof.

Throughout the drawings the broken lines depict portions of the multi-functional LED headlamp that form no part of the claimed design.
